UNITED STATES PATENT OFFICE.

MAX SLOANE, OF BROOKLYN, NEW YORK, ASSIGNOR TO SLOANE BROTHERS, OF BROOKLYN, NEW YORK, A COPARTNERSHIP COMPOSED OF MAX SLOANE AND NATHAN SLOANE, BOTH OF BROOKLYN, NEW YORK.

FASTENER FOR HANDBAGS.

1,392,712.

Specification of Letters Patent.

Patented Oct. 4, 1921.

Application filed November 16, 1920. Serial No. 424,380.

To all whom it may concern:

Be it known that I, MAX SLOANE, a citizen of Russia, and a resident of the city of New York, borough of Brooklyn, county of 5 Kings, and State of New York, have invented a new and Improved Fastener for Handbags, of which the following is a full, clear, and exact description.

This invention relates to hand bags, and 10 has for its general object to provide a novel fastener different from the usual fasteners, upon which reliance may be placed to hold the bag in closed position, and make the surreptitious opening of the bag attended with 15 greater difficulties than when reliance is placed solely upon the clasps or the catch usually provided on bags at the top.

The nature of the invention and its distinctive features and advantages will appear 20 as the description proceeds.

Reference is to be had to the accompanying drawings, it being understood that the drawings are merely illustrative of two examples of the invention.

25 Figure 1 is a perspective view of a bag having my improved locking means.

Fig. 2 is an enlarged fragmentary front view showing a portion of a bag and its frame, the latter provided with my improved fastener.

Fig. 3 is a longitudinal vertical section as indicated by the line 3-3 in Fig. 5.

Fig. 4 is a longitudinal vertical section on the line 4-4 of Fig. 5.

35 Fig. 5 is a fragmentary front view similar to Fig. 2 but with the finger hold removed and the shank of the fastening means shown in section, the view being given to illustrate a slightly modified embodiment of the invention.

40 Fig. 6 is a view similar to Fig. 4, but illustrating a modification.

In the illustrated example, A, A¹ designates the usual hinged frame members of a 45 bag B. C indicates a handle and D a fastener, all of which parts may be of any approved form, said fastener being shown as having a latch d of known form and constituting no part of my invention.

50 My invention is adapted to a frame in

which the frame members A, A¹ present respectively front and rear depending flanges 10, 10^a, 11, and 11^a. In the flanges 10, 10^a of the one frame member at A, I form alined longitudinal slots 12, 12^a, and in the adjacent depending flange 11^a of the other frame member A¹ is formed registering keyhole slot 13. Extending transversely through the slots 12, 12^a is the shank 14 of my improved fastener, said shank having a finger hold 55 15 thereon, at the outer side of the frame member whereby to slide the fastener longitudinally of the frame, to and from the fastening position. The inner end of the shank 14 projects laterally beyond the inner face 60 of the frame member A and is formed with a suitable head 16 or equivalent formation. The head 16 is spaced from the adjacent frame member 10^b through which the shank 14 projects to accommodate the adjacent 65 flange 11^a of the other frame member A¹. In the release position of the fastener, the shank 14 and its head 16 will be in line with the enlarged end 13^a of the keyhole slot 13, permitting said head to pass outwardly 70 through said opening with the fingers of the member A carrying the fastener in the opening of the bag. On the other hand, in the closed position of the bag, the head 16 will readily pass through the enlarged end 13^a 75 80 of the keyhole slot 13 to lie within the frame member A¹ between the inner and outer flanges 11, 11^a thereof.

To fasten the bag, the finger hold 15 is grasped and the fastener slid longitudinally 85 to dispose the shank 14 and its head 16 at that end of the keyhole slot 13 opposite the enlarged end 13^a, whereby the said head 16 will engage the flange 11^a, the fastener thereby being prevented from withdrawal from 90 the frame member A¹, thus holding the frame members in the closed position.

The several depending frame flanges are given an increased vertical dimension adjacent at the center of the frame to provide 95 the necessary strength in withstanding the possible weakening of the flanges by formation of the slots 12, 12^a, and 13. In the form of the invention shown in Fig. 6, the frame member A may have the slots thereof, one of 100

which is shown or designated at 12^b, formed with the ends dropped somewhat after the manner of a bayonet slot.

I provide means to hold my improved fastener either in the fastening or release position but yieldable to pressure exerted longitudinally on the finger hold 15, for which purpose I provide a bowed spring 17 disposed longitudinally within the frame A at 10 the top, the spring adjacent to its central portion having an additional curved bend 17^b, thereby producing a slight shoulder at each side of the center, and in the path of movement of the shank 14 in either direction. 15 Said spring may be suitably fastened at its ends 17^a to the top of the frame A.

With the described construction, assuming the bag to be open, the clasp will be positioned with the shank 14 at the right hand 20 end of the slots 12, 12^a or 12^b, the head 16 being thus transversely in line with the enlarged end 13^a of the keyhole slot 13. The bag having been closed, and the head 16 thereby caused to pass through the slot 13 25 through the enlarged end 13^a, the element 15 is grasped and the fastener moved longitudinally of the frame, the spring 17 yielding to the pressure of the shank 14 by the engagement of said shank with the curved central 30 portion 17^b of the spring. After the shank 14 has passed the central portion 17^b of the spring, said central portion snaps behind the shank thereby holding the fastener in the fastening position to prevent accidental 35 longitudinal sliding of the fastener to release position. To open the bag, the element 15 is slid in the reverse direction to bring the head 16 into alignment with the enlarged end 13^a of the slot 13.

40 In the form shown in Fig. 6 the spring 17 will depress the shank 14 into either slot end 12^c according to the release or fastening position of said shank, and thereby give increased security against the shifting of the 45 fastener from a given position.

It will be observed that the shank 14, in the preferred form as illustrated, is flat, and thereby the said shank and its finger hold 15 are prevented from turning movement so 50 that the finger hold will always remain disposed longitudinally of the frame. It will be noted also that I so position the slots 12, 12^a, 12^b, and 13 that the finger hold 15 will be in position centrally on the bag frame 55 when in the fastening position.

I would state in conclusion that while the illustrated example constitutes a practical embodiment of my invention, I do no limit myself strictly to the mechanical details 60 herein illustrated since manifestly the same can be considerably varied without departure from the spirit of the invention as defined in the appended claims.

What I claim is:

65 1. A bag frame comprising hingedly con-

nected members movable to the open or the closed position, a fastener disposed transversely on one frame member and projecting beyond the same to enter the other frame member, said frame members having longitudinal slots, and said fastener being movable in said slots to the fastening or the release position; together with a spring pressing against a longitudinal surface of the fastener and exerting friction on said fastener 75 to prevent accidental sliding of the same.

2. A bag frame comprising members movable to the closed or the open position, each frame member presenting depending spaced flanges, the flanges of one member having alined slots, a fastener having a shank movable in said slots, said shank having a finger hold thereon at the outside of the frame for manipulating the fastener, the inner end of said shank extending beyond said frame member, and provided with a head, the other of said frame members having a keyhole slot through the enlarged end of which said head may pass; said slot alining with the first mentioned slots. 90

3. A bag frame comprising members movable to the closed or the open position, each frame member presenting depending spaced flanges, the flanges of one member having alined slots, a fastener having a shank movable in said slots, said shank having a finger hold thereon at the outside of the frame for manipulating the fastener, the inner end of said shank extending beyond said frame member and provided with a head, the other of said frame members having a keyhole slot through the enlarged end of which said head may pass, said slot alining with the first mentioned slots; together with a spring 95 within the first mentioned slotted frame member, and frictionally engaging said shank to prevent accidental movement of the same in the slots. 100

4. A bag frame comprising members movable to the closed or the open position, each frame member presenting depending spaced flanges, the flanges of one member having alined slots, said slots ranging longitudinally of said member and the ends of the slots extending downwardly, a fastener having a shank movable in said slots, said shank having a finger hold thereon at the outside of the frame for manipulating the fastener, the inner end of said shank extending beyond the said slotted frame member and provided 115 with a head, the other of said frame members having a keyhole slot through the enlarged end of which said head may pass, said slot alining with the first mentioned slots. 120

5. A bag frame comprising members movable to the closed or the open position, each frame member presenting depending spaced flanges, the flanges of one member having alined slots, a fastener having a shank movable in said slots, said shank having a finger 125

hold thereon at the outside of the frame for manipulating the fastener, the inner end of said shank extending beyond said frame member, and provided with a head, the other 5 of said frame members having a keyhole slot through the enlarged end of which said head may pass, said slot alining with the first mentioned slots; together with a bowed spring having a central bent portion presenting shoulders and frictionally engaging said 10 shank to prevent accidental movement of the same.

MAX SLOANE.
